ABSTRACT: An apparatus comprises folding and sealing stations for progressively folding adhesively treated carton flaps into superimposed relationship and for sealing the flaps together. The folding may be occasioned by a horizontally disposed tucker wheel positioned on each side of the carton for folding three minor flaps and a plow bar for folding a cover flap over the aforementioned minor flaps. The carton is then conveyed to the sealing station whereat a nozzle means moves along with the carton to discharge heated air onto juxtaposed portions of the carton flaps. Means are then provided for compressing the flaps together. A second embodiment incorporates the nozzle means into the tucker wheel to perform the folding and sealing steps substantially simultaneously.

APPARATUS AND METHOD FOR CLOSING AND SEALING CARTONS

The popularity of frozen food packaging dictates the need for apparatus and methods whereby the closure flaps of cartons may be folded and sealed expeditiously and economically. The availability of heat sealable adhesives or coatings, such as polyethylene, has encouraged the packaging art to employ heated air for expeditiously activating such adhesive prior to sealing. For example, U.S. Pat. No. 3,389,645, assigned to the assignee of this application, discloses an apparatus and method employing heated air for carton-sealing purposes.

In general, packaging speeds are dictated by the ability of a machine to efficiently fold and tightly seal a carton's closure flaps without distorting, scarring or otherwise impairing the carton's appearance or structural integrity. Folding and sealing problems are particularly apparent with respect to the so-called top-loaded frozen food cartons which may comprise relatively lengthy but narrow flaps which are more readily prone to leakage than conventional flaps. It has been found that the apparatus and method of this invention is capable of efficiently folding and sealing carton closure flaps at speeds substantially higher than packaging speeds achieved by conventional apparatus and methods.

General objects of this invention are to provide an apparatus and method for expeditiously and economically folding and sealing adhesively treated portions of carton flaps together. This invention is particularly useful for forming a carton closure exhibiting high structural integrity and leakage resistance. The apparatus comprises conveying means for moving a carton through a folding means to fold and juxtapose at least two carton flaps. Nozzle means are movably mounted in the apparatus for discharging a heated fluid onto the flaps. Flap-closing means are positioned for thereafter compressing and sealing the flaps together.

The folding means of a first-described embodiment comprises at least one tucker wheel rotatably mounted adjacent to the conveying means. The nozzle means is mounted in the apparatus to move in the general direction of the conveying means for simultaneously discharging the heated fluid, preferably air, onto the folded carton flaps. A second described embodiment incorporates a nozzle means into at least one tucker wheel to thus perform the folding and sealing operations at the same location in the apparatus.

Other objects of this invention will become apparent from the following description and accompanying drawings wherein:

FIG. 1 is a side elevational view of an apparatus employing novel features of this invention therein with parts broken away for clarification purposes;

FIG. 2 is an isometric view of a partially erected carton adapted to have closure flaps thereof closed and sealed pursuant to teachings of this invention;

FIG. 3 is a top plan view of the FIG. 1 apparatus with parts broken away for clarification purposes;

FIG. 4 is an enlarged, top plan view of a folding station employed in the FIGS. 1 and 3 apparatus;

FIG. 5 is a partially sectioned, front elevational view of the folding station taken in the direction of arrows 5-5 in FIG. 4;

FIGS. 6-11 are enlarged, fragmentary views of a tucker wheel employed in the folding station illustrating the tucker wheel in progressive states of operation;

FIG. 12 is a sectional view of a portion of the tucker wheel;

FIG. 13 is an enlarged, top plan view of a sealing station employed in the FIGS. 1 and 3 apparatus with parts broken away for clarification purposes;

FIG. 14 is a side elevational view of the sealing station illustrated in FIG. 13 with parts broken away for clarification purposes;

FIG. 15 is an enlarged, fragmentary view clearly illustrating the disposition of a portion of a chain drive shown in FIG. 14;

FIG. 16 is a cross-sectional view of the sealing station, taken in the direction of arrows 16-16 in FIG. 13;

FIG. 17 is an enlarged, fragmentary view more clearly illustrating a portion of a sealing arrangement shown in FIG. 16;

FIG. 18 is a top plan view of a U-shaped nozzle means employed in the sealing station with portions thereof broken away for clarification purposes;

FIG. 19 is an isometric view of the nozzle means;

FIG. 20 is a partially sectioned top plan view of a modified folding and sealing means;

FIG. 21 is a sectional view taken in the direction of arrows 21-21 in FIG. 20;

FIG. 22 is a sectional view taken in the direction of arrows 22-22 in FIG. 20;

FIG. 23 is a top elevational view of the FIG. 20 folding and sealing means in an advanced stage of operation; and

FIG. 24 is a sectional view taken in the direction of arrows 24-24 in FIG. 23.

Referring to FIGS. 1 and 3, the illustrated apparatus comprises a folding station or means 30 and a sealing station or means 31 adapted to have cartons C continuously conveyed therethrough by conveying means, preferably in the form of an endless conveyor belt 32. The conveying means functions to retain and move the cartons along a path or line of flight during all phases of the folding and sealing operations. The drive means therefor will be hereinafter described during the course of describing the integrated, overall drive system for the apparatus. It should be understood that the term path may be interpreted to mean a path other than the straight and horizontal one illustrated, e.g., vertical, arcuate, etc.

The illustrated carton is of the top-loading type comprising a single blank suitably cut and scored and partially erected to its FIG. 2 condition. The partially erected carton may comprise a horizontally disposed bottom panel P₁ having vertically disposed side panels P₂ and P₃ and front and rear panels P₄ and P₅, respectively, connected thereto. A cover flap or top panel F₁ is hingedly connected at a scoreline to the top edge of rear panel P₅ whereas vertically disposed minor flaps F₂, F₃ and F₄ are connected in a similar manner to panels P₂, P₃ and P₄, respectively. A tear line T₁ may be formed in front panel P₄ and flap F₄ to define a removable tab adapted to tear open top flap F₁ at tear lines T₂ after the top flap has been secured to minor flaps F₂-F₄ to form a closed carton.

Each carton is delivered to and trapped between upstanding lugs or plates 33 and 34 secured to conveyor 32 (FIGS. 1 and 3). It should be noted in FIG. 7, for example, that lug 34 preferably has a height substantially equal to the height of front panel P₄. The lug thus provides backup means to aid in preventing the panel and attached flap F₄ from buckling or otherwise distorting during subsequent folding and sealing operations. It should be further noted that lug 33 may comprise a height substantially less than the height of lug 34 since such distortion problem is not apparent thereat.

Folding assemblies 35 and 36 are each mounted on a respective side of the conveying means to first fold flaps F₂ and F₃ to a horizontally disposed position and to then fold flap F₄ thereover. Since the folding assemblies are substantially identical, only assembly 36 will be described in detail with particular reference being afforded to FIGS. 4-12. The folding assembly comprises a horizontally disposed tucker means or wheel 37 secured to a vertically disposed shaft 38 to rotate therewith.

The tucker wheel comprises a plurality of folding members 39, each member being adjustably mounted on the periphery of the wheel by an arcuate slot and bolt connection 40. Thus, each folding member may be adjusted about the longitudinal axis of shaft 38 to adjust the assembly for the folding of carton flaps having varied dimensions. Although four folding members are employed on the illustrated tucker wheel, any desired number thereof may be employed depending on the particular packaging application under consideration.

The tucker wheels function to gradually engage and fold flaps F₂-F₄ by having portions thereof move substantially in the direction of the scoreline hingedly connecting each flap to the carton. Such gradual folding prevents the carton's side panels P₂-P₄ (FIG. 2) from buckling or otherwise distorting. In addition, such portions function to gently push the product (not shown) towards the center of the carton. The linear or

surface speed at the folding portions of each tucker wheel are preferably substantially equal to the linear speed of the conveying means to alleviate carton drag.

Referring to FIG. 6, the folding member comprises a rounded, leading first finger means or portion 41 connected to an arcuate portion 42. Edge 43 of portion 42 preferably comprises a constant radius R, the center of such radius being the longitudinal axis of shaft 38 (FIG. 4). The edge terminates at its trailing end at a slot 44, primarily employed for effecting a smooth transitional folding change prior to when a curved edge 45 of a trailing second finger means or portion 46 engages and folds trailing minor flap F₄. The radius of edge 45 is substantially greater than radius R as clearly illustrated in the drawings.

Referring to FIG. 11, it should be noted that finger 46 is preferably tapered toward its trailing end to permit cover flap F₁ to be superimposed over flaps F₂—F₄ to retain them thereunder prior to when finger 46 moves out of the confines of the carton. Conveyor 32 proceeds to move the cartons leftwardly in FIG. 3 with such cartons being guided on each side thereof by stationary bars 49 and 50. A stationary plow means or bar 51 (FIGS. 1 and 3) is arranged adjacent to and vertically above tuckers 37 to engage and fold cover flap F₁ over flaps F₂—F₄. The plow bar comprises a horizontally disposed extension 52 which partially extends into the sealing station to assure that flap F₁ is held down prior to its transfer into the sealing station.

With carton flaps F₁—F₄ superimposed, conveyor 32 proceeds to move the carton through sealing station 31 to secure the flaps together. The flaps are preferably adhesively treated when the carton blank is formed initially. The term "adhesive" as used herein should be understood to mean any preapplied fusible coating adapted to be activated by heat for sealing carton panels or flaps together. For example, such adhesive may constitute a heat-sealable wax, polyethylene, polyvinylchloride or the like. The carton may constitute paperboard or any other suitable packaging material partially or totally coated with such an adhesive.

The sealing station comprises laterally spaced and vertically disposed parallel endless chains 60 and 61 or carrier means (FIG. 14) mounted in staggered relationship on a stationary frame 62 of the machine and on a respective side of the conveying means. The chains are arranged to form an endless carrier means for moving a respective U-shaped member or nozzle means 63, attached therebetween, into juxtaposed and substantial surrounding relationship with respect to three sides of each carton. Chain 60 is mounted on sprockets 64 and 65, secured to shafts 66 and 67, respectively. Chain 61 is mounted on sprockets 68 and 69 which are respectively secured to shafts 70 and 71 for rotation therewith. The drive input to such chains, suitably integrated into the overall drive system of the apparatus, will be hereinafter more specifically described.

As clearly illustrated in FIGS. 13—15, each shoelike member or nozzle means 63 comprises upstanding and diametrically spaced lugs 72 and 73 pivotally mounted to chains or endless carrier means 60 and 61 by pivot pins 74 and 75, respectively. Lugs 72 and 73 may have apertures 76 and 77 formed therethrough, respectively, to prevent undue conduction of heat upwardly through the lugs. The chains are constructed and arranged to continuously maintain the members horizontal and to move them in a closed, semirectangular path, as noted by the transition of member 63 from its raised to its lowered position in FIG. 14. As shown in FIGS. 18 and 19, each shoe comprises a cast U-shaped member 80 having a matching U-shaped cover plate 81 suitably secured thereto by brazing or other suitable fabrication technique.

The cast member is substantially hollow to define intercommunicating chambers 82, 83 and 84 therein. Elongated openings or slots 85 and 86 are formed through opposite sidewalls of member 80 and defined in part by plate 81 to communicate with chambers 82 and 84, respectively. Stationary heater assemblies 87 and 88 (FIGS. 16 and 17) are

each mounted on a respective side of the apparatus to communicate heated air through the slots. Member 80 and plate 81 further define elongated nozzles 90, 91 and 92 communicating with chambers 82, 83 and 84, respectively.

5 The nozzles in turn communicate heated air, maintained at a suitable temperature (e.g., 900° F.) and pressure (e.g., 5 p.s.i.), to the carton flaps to activate the adhesive preformed thereon. In an actual application the width or height of each 10 nozzle approximated one-sixteenth of an inch. It should be noted in FIG. 15 that the trailing side of member 80 preferably has a vertically disposed slot 93 formed therein to provide a suitable clearance for the forward end of holdown bar portion 52 (FIG. 15). In particular, such clearance is desirable when member 63 makes its descent into its substantial encircling position with respect to the carton.

As illustrated in FIGS. 14 and 15, a boxlike housing 95 of a first cooling and flap-positioning means is suitably secured to the frame of the machine and forms a horizontally disposed lower surface 96 thereon. Such surface is arranged to engage top flap F₁ to maintain it in its correct, spaced position (e.g., one-eighth of an inch) relative to the flaps F₂—F₄. The inherent resiliency of flap F₁ aids in maintaining it slightly spaced from flaps F₂—F₄ during the sealing operation.

20 Nozzles 90—92 are arranged slightly lower than surface 96 (FIG. 17) to discharge heated air onto and between the opposed flaps. A forward end 97 of the housing may be tapered upwardly in the manner shown to facilitate reception of the carton thereunder. Thus, it can be seen that the carton will experience a smooth transition from the folding station to the sealing station with flap F₁ being smoothly moved from the undersurface of hold-on bar portion 52 to coplanar surface 96 of housing 95.

25 Housing 95 of the cooling means preferably comprises chambers 100 and 101 (FIG. 16) adapted to continuously circulate a cooling fluid therethrough, such as water maintained at approximately 50° F. The cooling fluid may be circulated through the chambers by a closed circulating system comprising suitable pump and cooling means (not shown) and inlet means 102 and outlet means 103 (FIG. 3), for example. The cooling means primarily functions to prevent overheating, scorching or marking of the carton by providing a suitable "heat sink" over the entire top surface of cover flap F₁ during sealing.

30 A second cooling or flap-closing means, substantially identical to the first cooling means, comprises a housing 105 aligned with housing 95 to receive the cartons thereunder. The second cooling means comprises a horizontally disposed lower surface 106 vertically arranged slightly lower (e.g., one-eighth of an inch) than surface 96 of the first cooling means. In particular, surface 106 functions to cool and to fully compress and seal cover flap F₁ to flaps F₂—F₄ to form a tightly sealed closure. Housing 105 also forms suitable circulating chambers 35 therein (not shown) which may have cool water circulated therethrough from an inlet 107 (FIG. 3) to a suitable outlet of the cooling system. Side compression and cooling bars 108 and 109 may be suitably connected to such inlet and outlet and arranged on opposite sides of the carton to aid in "squaring" the cartons and for further cooling the sealed areas.

35 Returning to FIG. 17, each heating means 87 and 88 may comprise a heater and attendant constructions similar to those disclosed in U.S. Pat. application Ser. No. 735,000, filed on June 6, 1968 by George Schafer et al. for "Apparatus and Method for Forming Cartons." In particular, each heater may comprise a tubular manifold 110 secured to a casing having vertically disposed electrical heating coils (not shown) suitably disposed in chambers thereof. Ambient air, maintained at a suitable pressure, passes by and around the coils to be heated to a predetermined temperature prior to when it is discharged from nozzle 110 and through elongated opening 85.

40 It should be noted that the flat, front surface 112 of manifold 110 (FIG. 17) and juxtaposed surface 113 of the

nozzle means are in substantial bearing and sliding contact to prevent heated air from escaping thereby and to aid in laterally positioning the nozzle means. In addition, housing 95 preferably extends laterally a slight distance to overlie a recessed, top edge portion of the nozzle means to provide means for aiding in the correct positioning of the nozzle means during its air-discharging function. In addition, parallel ribs 113 and 114 are preferably formed on cover plate 81 (FIG. 19) to aid in laterally positioning the nozzle means relative to housing 95 and cartons C. Such ribs further function to aid in preventing heated air from escaping between the housing and nozzle means when it is discharged out of nozzles 90 and 92.

The integrated drive means for driving the various components of the above-described apparatus will now be described. Referring to FIG. 1, a main electrical drive motor 115 has an output shaft 116 adapted to selectively drive a sprocket 117. The sprocket in turn drives an endless chain 118 and sprocket 119 to impart movement to conveyor means or belt 32 via a shaft 120 and drive sprocket 121. A first spur gear 122 (FIG. 3) is secured to shaft 120 and meshes with a second spur gear 123 to drive a shaft 124. Shaft 124 has a sprocket 125 secured thereto which in turn drives an endless chain 126 to impart rotation to a sprocket 127.

The latter sprocket is secured to a shaft 128 which in turn functions to drive endless chains 129 and 130 via suitably arranged sprockets (not shown). The latter two chains are operatively connected to shafts 67 and 71 by sprockets 65 and 69, respectively, to simultaneously drive chains 60 and 61.

Conveyor 32 is mounted on sprocket 121 and a second idler sprocket 131, the latter sprocket being secured to a horizontally disposed shaft 132. The shaft rotates with sprocket 131 to drive a sprocket 133, chain 134, and sprocket 135 to impart rotation to a shaft 136. The latter shaft is operatively connected to shaft 38 of folding means 35 and 36 by suitable drive mechanisms 137 and 138, illustrated in FIG. 5.

As further illustrated in FIG. 1, a blower 139 of the positive displacement type may have its shaft 140 suitably integrated into the above-described drive system to rotate the blower's vanned rotor (not shown). Such actuation will communicate pressurized air through branch conduits 141 which are connected at their other ends to above-described heater assemblies 87 and 89 (FIG. 16). From the above description it can be seen that all moving parts employed in the apparatus are suitably integrated to perform all operations in a synchronized manner.

FIGS. 20-24 illustrate a modified folding and sealing means embodiment wherein the folding and sealing stations are at the same location. The two embodiments employ common numerals to depict constructions and arrangements exhibiting substantially identical functions with the FIGS. 20-24 numerals being accompanied by a subscript *a*. It should be further understood that the type of conveying and final sealing means employed in the first-described embodiment may also be utilized in conjunction with the embodiment now to be described.

Cartons C are continuously conveyed through the consolidated folding and sealing stations illustrated in FIG. 20 by suitable conveying means. Folding and sealing assemblies 36a and 37a are substantially identical and therefore only assembly 36a will be described in detail. Such assembly comprises a cylindrical drum 37a adapted to be rotated about a vertically disposed axis thereof by drive means suitably integrated into the overall drive system for the apparatus.

A plurality of folding members or means 39a (one shown) are secured on the periphery of the drum assembly to fold flaps F₁-F₄ into juxtaposed relationship. As will be hereinafter explained each member 39a further functions as a nozzle means for discharging a heated fluid onto the carton flaps for sealing purposes.

Member 39a comprises a rounded leading first finger means or portion 41a connected to an arcuate portion 42a. Edge 43a of portion 42a preferably comprises a constant radius, the center of such radius being the longitudinal axis of drum as-

sembly 37a. The edge terminates at its trailing end at a slot 44a primarily employed for effecting a smooth transitional folding change prior to when a curved edge 45a of a trailing second finger means or portion 46a engages and folds trailing minor flap F₄.

A stationary plow means or bar 51a (FIG. 22) is arranged to engage and fold flap F₁ over flaps F₂-F₄. Such bar may be constructed and arranged similar to bar 51 of the first-described embodiment to guide the carton to the final compression and sealing means or may comprise such means itself. As described above the flaps are preferably adhesively treated when the carton blank is formed initially to permit a heated fluid to be discharged thereon for sealing purposes.

Member 39a is preferably cast to be substantially hollow to define intercommunicating chambers 82a and 83a therein. An arcuate opening or slot 85a is formed in member 39a to communicate with chamber 82a. Drum assembly 37a may have a large chamber 110a (FIG. 20) formed therein to communicate heated air to slot 85a. The heated air may be communicated to chamber 110a in any conventional manner such as by the type of heating assembly 87 employed in the first-described embodiment.

Thus it can be seen that the folding and sealing operations are performed substantially simultaneously in contrast to the somewhat delayed and sequential folding and sealing steps employed in the first-described apparatus. The linear or surface speed of the finger means is preferably substantially equal to the linear speed of the conveying means to assure complete activation of the flap's adhesive by the nozzle means and to eliminate carton drag. As stated above the carton may be then passed under a stationary compression means such as a plow bar to fully compress flap F₁ over flaps F₂-F₄.

It can be seen that both of the above-described embodiments are adapted to perform a method for sealing at least two adhesively treated carton flaps together. The method may generally comprise the steps of: conveying carton C along a path; folding the flaps into substantially superimposed and spaced relationship; moving a nozzle means along said path and simultaneously maintaining said nozzle means adjacent to said carton flaps; discharging a heated fluid onto the carton flaps to activate the adhesive thereon; and compressing and sealing the flaps together.

We claim:

1. An apparatus for folding and sealing adhesively treated carton flaps together comprising:
conveying means for moving a carton having adhesively treated flaps hingedly connected thereto along a path;
folding means for folding said flaps into juxtaposed relationship;
nozzle means movably mounted in said apparatus for discharging a heated fluid onto said folded carton flaps during simultaneous movement of said carton and said nozzle means;
means for moving said nozzle means simultaneously with said conveying means at least partially along said path and in close proximity to said carton flaps for permitting said discharge of a heated fluid thereon; and
flap-closing means for compressing and sealing said flaps together.
2. The invention of claim 1 wherein said folding means comprises at least one horizontally disposed tucker means mounted for rotation adjacent to said conveying means for engaging and folding at least one carton flap to a substantially horizontal position.
3. The invention of claim 2 wherein said folding means comprises two of said tucker means mounted for rotation on opposite sides of said conveying means for engaging and folding three carton flaps into substantially horizontal and superimposed positions.
4. The invention of claim 2 wherein said tucker means comprises a tucker wheel mounted for rotation adjacent to said conveying means and having a plurality of folding members mounted on the periphery thereof, each of said folding mem-

bers comprising a leading first finger portion for engaging and folding a first carton flap laterally inwardly toward said path and a trailing second finger portion for engaging and folding a second carton flap, arranged perpendicular relative to said first flap, in said first direction along said path.

5. The invention of claim 1 wherein said folding means comprises a stationary plow means arranged adjacent to and vertically above said conveying means for folding and superimposing a cover flap over said other flaps.

6. The invention of claim 5 further comprising a horizontally disposed flap-positioning means disposed vertically above said conveying means and adjacent to said plow means for engaging and holding said cover flap over and slightly spaced from said other flaps.

7. The invention of claim 6 further comprising means for circulating a cooling fluid through said flap-positioning means.

8. The invention of claim 1 wherein said nozzle means is mounted for movement on an endless carrier means for continuously maintaining said nozzle means substantially horizontal and parallel relative to said path.

9. The invention of claim 8 wherein said carrier means comprises laterally spaced and vertically disposed parallel endless chains mounted in staggered relationship at opposite sides of said conveying means.

10. The invention of claim 9 wherein said nozzle means comprises diametrically spaced lugs each pivotally attached to one of said chains.

11. The invention of claim 1 wherein said nozzle means comprises a member having at least one elongated nozzle formed therein to be substantially parallel to said path and further comprising means, including a stationary heater assembly mounted alongside said conveying means, for communicating heated fluid to said nozzle through said nozzle means.

12. The invention of claim 1 wherein said flap closing means is horizontally disposed and positioned vertically above said conveying means for engaging and compressing a cover flap over said other flaps to form a tightly sealed closure.

13. The invention of claim 12 further comprising means for circulating a cooling fluid through said flap-closing means.

14. The invention of claim 1 further comprising drive means for simultaneously actuating said conveying, folding and nozzle means in synchronized relationship.

15. The invention of claim 1 wherein said folding means has said nozzle means formed therein.

16. The invention of claim 15 wherein said folding means comprises at least one horizontally disposed tucker means mounted for rotation adjacent to said conveying means, said nozzle means comprising a plurality of orifices formed on the periphery of said tucker means, whereby at least one carton flap may be folded and simultaneously have said heated fluid discharged thereon.

17. The invention of claim 16 wherein said tucker means is substantially hollow to form a chamber therein and is attached to the periphery of a drum assembly, said drum assembly also forming a chamber therein communicating with the chamber formed in said tucker means and means for supplying said heated fluid to the chamber of said drum assembly.

18. The invention of claim 16 wherein two of said tucker means are mounted for rotation on opposite sides of said conveying means.

19. The invention of claim 1 wherein said folding means is positioned for folding and superimposing at least portions of upstanding first and second flaps, said first flap hingedly connected to said carton by a first scoreline disposed in the direction of said linear path and said second flap hingedly connected to said carton by a second scoreline disposed perpendicularly relative to said first scoreline, said folding means comprising a horizontally disposed tucker means mounted for rotation about a vertically disposed axis thereof adjacent to said conveying means, said tucker means having a first finger means for gradually engaging and folding said first flap laterally inwardly toward said linear path by moving substantially in the direction of said first scoreline and progressively

along said first flap and a second finger means for gradually engaging and folding said second flap into superimposed position over at least a portion of said first flap by moving substantially in the direction of said second scoreline and progressively along said second flap, the radius of said second finger means being substantially greater than the radius of said first finger means with each of said radii being centered at the vertically disposed axis of said tucker means.

20. The invention of claim 19 wherein said tucker means further comprises notch means formed between said first and second finger means for permitting said second finger means to initiate its folding of said second flap at said notch means.

21. The invention of claim 19 further comprising means for adjustably mounting said first and second finger means on the periphery of said tucker means.

22. The invention of claim 19 wherein said tucker means comprises a tucker wheel having a plurality of said first and second finger means mounted on the periphery thereof.

23. The invention of claim 1 wherein said means for moving said nozzle means in the general direction of movement of said conveying means moves at substantially the same linear speed as said conveying means.

24. The invention of claim 1 wherein said nozzle means is U-shaped and has an elongated nozzle formed at each side thereof.

25. The invention of claim 1 wherein at least two of said flaps are hingedly connected to said carton to be perpendicular relative to each other, said nozzle means comprising means forming first and second nozzles arranged at least substantially perpendicular with respect to each other for discharging heated fluid onto respective ones of said two carton flaps, said first and second nozzles being disposed substantially coplanar with respect to each other.

35. 26. The invention of claim 25 wherein said nozzle means comprises a U-shaped member having said nozzles formed interiorly thereon.

27. The invention of claim 25 wherein said nozzle means is rotatably mounted in said apparatus.

40. 28. An apparatus for folding and sealing carton flaps together comprising:

conveying means for moving a plurality of cartons along a horizontally disposed line of flight, each of said cartons comprising four substantially vertically disposed and adhesively treated flaps hingedly connected thereto;

50 a horizontally disposed tucker means rotatably mounted on each side of said conveying means for folding three of said carton flaps into superimposed relationship; stationary plow means arranged adjacent to and vertically above said tucker means for engaging and folding a fourth one of said flaps over the three flaps folded by said tucker means;

55 a horizontally disposed cooling and flap-positioning means disposed vertically above said conveying means for engaging and holding said fourth flap over and slightly spaced from said other three flaps;

laterally spaced and vertically disposed parallel endless chains each mounted on a respective side of said conveying means and having a plurality of U-shaped nozzle means attached therebetween for moving each nozzle means in substantial surrounding relationship with respect to said three carton flaps;

elongated nozzles formed in said nozzle means to discharge a heated fluid onto said flaps to activate said adhesive;

a stationary heater assembly mounted on each side of said conveying means and having an elongated manifold juxtaposed to an elongated slot formed externally in said nozzle means, said slot communicating with said nozzle; means for communicating a heated fluid to said manifold; and

a horizontally disposed flap cooling and closing means disposed vertically above said conveying means for engaging and compressing said fourth flap over said other three flaps to form a tightly sealed closure.
